UNITED STATES PATENT OFFICE.

HARRY J. DEUTSCH, OF COLUMBUS, OHIO.

DESIGN FOR A WIND-WHEEL.

53,490.

Specification for Design.

Patented July 8, 1919.

Application filed May 11, 1918. Serial No. 234,029. Term of patent 3½ years.

To all whom it may concern:

Be it known that I, HARRY J. DEUTSCH, a citizen of the United States, residing at Columbus, in the county of Franklin and State of Ohio, have invented a new, original, and ornamental Design for Wind-Wheels, of which the following is a specification, reference being had to the accompanying drawing, forming part hereof.

In said drawing—

Figure 1 is a view in side elevation of the design, and

Fig. 2 is a top plan view.

I claim:

The ornamental design for a wind wheel, as shown.

HARRY J. DEUTSCH.
